UNITED STATES PATENT OFFICE.

MATT. J. BOGERT, OF DEMAREST, NEW JERSEY.

DESIGN FOR A BOX.

SPECIFICATION forming part of Design No. 20,356, dated December 2, 1890.

Application filed August 12, 1890. Serial No. 361,823. Term of patent 7 years.

To all whom it may concern:

Be it known that I, MATT. J. BOGERT, a citizen of the United States, residing at Demarest, in the county of Bergen and State of New Jersey, have invented and produced a new and original Design for Globe-Lantern Boxes; and I do hereby declare the following to be a full, clear, and exact description of the same, reference being had to the accompanying drawings, forming a part thereof.

My invention has relation to a design for a box; and it consists in the shape and novel arrangement of parts, as hereinafter more fully described, illustrated in the accompanying drawings, and pointed out in the appended claim.

In the drawings, Figure 1 is a side view of my design for a box, which is a general representation of a globe-lantern. Fig. 2 is a vertical transverse section of the same.

Referring to the accompanying drawings, in which like letters of reference indicate corresponding parts in both the figures, the letter A designates my design for a box, which is

made to represent a globe-lantern, and consists of the base B, formed by a series of convex ribs C, three in number. 25

The letter D designates the body portion, which is of a general elliptical form upon its exterior surface and provided with a central 30 hollow space E, the walls of which are vertical, as shown.

At the upper end of the body portion D is the top G, which is provided with a shoulder H.

I represents the handle, which is in the form 35 of the letter U, the legs of which are bent at right angles.

Having thus fully described my invention, what I claim as new, and desire to secure by Letters Patent, is—

A design for a lantern-box, as herein shown and described.

In testimony whereof I affix my signature in presence of two witnesses.

MATT. J. BOGERT.
